STABILIZER FOR TRAVERSING HOIST
BUCKETS

Willis H. Towne, Wilmette, Ill., assignor to Gifford-Wood Company, a corporation of New York

Application November 8, 1926, Serial No. 146,890

9 Claims. (C.I. 212—77)

This invention relates to traversing hoists of the type employing dumping buckets, and aims to prevent damage and eliminate delays resulting from the pendulum-like swinging set up by starting and stopping of the buckets.

The invention may be understood by reference to one illustrative embodiment shown in the accompanying drawings, in which:

Fig. 1 is an elevation, with parts broken away, illustrating a plant employing a traversing hoist provided with the bucket-stabilizing device;

Fig. 2 is an elevation on a much larger scale showing the bucket-stabilizing means; and

Fig. 3 is an end elevation of the same, showing the track in cross section.

Because of the heavy expense of repeated handling and long distance hauling of coal and other heavy materials, there has been a distinct trend of recent years toward the establishment of what may be termed "neighborhood" yards, that is to say, yards located in various sections of a city for the storage and handling and retail selling of coal, building materials and the like. The most modern yards are specially designed to be run with a minimum of labor, being served by sidings from a railroad, and so arranged that the coal or other material may be dumped from the railroad car and carried by a traversing hoist bucket to storage bins, from which wagons or trucks are easily loaded by gravity.

An installation of the character described has many advantages over a yard employing open air storage for coal, building materials or the like, which need not be explained. However, in use, certain operating difficulties are encountered which the invention seeks to obviate, as will be set forth below.

Referring to Fig. 1, there is shown a portion of a small neighborhood yard suitable for handling coal and like commodities, the supply of which is delivered by a railroad to a siding (not shown) built over a pit (not shown), permitting dumping of the coal as received. The bucket 5 obtains a load from the pit, and then moves over a plurality of concrete bins 6, each bin providing a compartment for one of the several kinds of coal which it is desired to keep in stock. The upper ends of the bins are open to permit the bucket 5 to descend therein for dumping its loads without unnecessary breakage of the coal; and for protection against the weather, said upper ends are covered by a shed 1 having an opening 8 to permit the bucket to pass into and out of the shed on its way to and from the bins. The elevated track 9 along which the bucket-carrying trolley

10 runs is supported by a structure 11 extending between the pit and the most remote bin. In the illustrative plant, the lower portions of the bins have lateral openings 12 of sufficient size to permit trucks to be driven underneath the bins and to receive loads from chutes 13 leading from the bottoms of the bins, as shown.

While the mechanism for operating the bucket is per se no part of my invention, the disclosure of certain portions of the bucket-operating means is necessary to make clear the nature and advantages of the invention. The bucket is raised or lowered by means of a hoist line 14 which extends to a motor driven hoist drum (not shown) located within the engine house 15. The arrangement is such that as the hoist drum is rotated in opposite directions the hoist line is wrapped upon or unwrapped from the drum, thus causing the bight 14a of the hoist line to be drawn in or paid out, as will be clearly understood, so that the vertical position of the bucket is controllable by a single line. The bucket has a bail 16 provided with a sheave 17, and the bight 14a of the hoist line passes around the sheave 17 and over sheaves 18 carried upon the trolley 10, and is made fast to one end of the track or other stationary member, being guided by an idler sheave 19 to the hoist drum. To propel the trolley, and hence the bucket, in opposite directions, a trolley line 20 is used, having its ends fixed at 21 to the opposite ends of the trolley and passing about an idler sheave 22 at one end of the track 9 and also over guide sheaves 23 and downwardly to the motor driven trolley drum (not shown) located in the engine house 15. By the described arrangement the position of the bucket is controlled with but two lines, each entirely independent of the other.

In the operation of the described plant, the bucket is moved into the pit and there receives its load, preferably by gravity as described in the application of C. M. Root, Serial No. 78,163, filed December 29, 1925, and is then hoisted sufficiently high to clear the tops of the bins and is moved along the elevated track until it is over one of the bins. The bucket is now lowered until its bottom comes in contact with the coal previously placed in the bin or else with the bottom of the bin if the bin is empty, and thereupon the bucket automatically dumps through its bottom, for instance as disclosed in the A. C. Bennett Patent No. 1,741,123, thus preventing much breakage. Its load being thus discharged, the bucket is then hoisted and returned to the pit for another load.

and the process is repeated until the supply of coal is stored, or until the bin is full.

In using the described apparatus, trouble is encountered because of the momentum of the bucket, particularly when loaded. Rarely will the bucket have a load capacity of less than 1 ton, and when empty it may weigh upwards of 2400 lbs., while its speed may be from 300 to 800 ft. per minute, depending on the extent of the plant and the size of the bucket. As the bucket is supported by a freely rotatable sheave movable over the relatively flexible bight 14a of the hoist line, when started or stopped it acts (whether loaded or empty) like an extremely heavy pendulum and hence continues to oscillate for a considerable time. If the start or stop is sudden, the oscillation is much more pronounced. When the bucket is adjacent the track these oscillations may simply move the trolley back and forth along the track; but if the bucket is lowered while oscillating, the pendulum formed by the bucket and the bight 14a of the hoist line becomes longer and therefore the arc traversed by the oscillating bucket becomes increasingly larger. The result is that the bucket sooner or later strikes against the inside wall of the concrete bin, thereby damaging said wall and frequently battering the bucket to such an extent as seriously to injure it. As installations of the described type are expressly built to lower operating costs, it is customary to employ only one operator, who must stay in the engine house. It is impossible for the single operator to see the bucket when it is in the bins or above the bins, and therefore damage resulting from swinging of a bucket cannot be foreseen and prevented. By the present invention, I provide a bucket stabilizing means which positively checks all oscillations of the bucket set up by starting and stopping of the trolley, and acts entirely automatically, permitting one-man operation.

A stabilizing means embodying my invention is shown in Figs. 2 and 3, and consists of an attachment to the trolley against which the bail of the bucket strikes upon elevation of the bucket. Preferably, the bail is pivoted to the bucket, which is supported by the hoist line so that the bail is normally parallel to the trolley. As shown, a frame 24 is fixed to each end of the trolley and extends below the trolley, supporting two buffer plates 25 which the bail of the bucket strikes when the bucket is raised to its uppermost position. The buffer plates have a sufficient spread to insure engagement of the bail therewith when the bucket has been elevated. Preferably, the buffer plates are parallel to each other, and extend at right angles to the plane of the track (and of the trolley) at equal distances from the ends of the trolley, spaced about as far apart as the ends of the trolley, and have both ends bent downwardly, as shown, serving, when the bucket is elevated while swinging, to guide the bail to a central position. Each frame carries two rods 26, the lower ends of which are secured to the buffer plates and the upper ends passing through angles of the frame and being secured by lock nuts 27. The rods 26 carry compressed coil springs 28 interposed between the buffer plates and the frame, the arrangement being such that any blow or stress communicated to the buffer plates by the bucket bail will further compress some or all of the springs. As there are two sets of springs at opposite ends of the trolley co-operating to resist swinging of the bucket bail 16 and therefore tending to hold the bucket bail

parallel to the track, it will be clear that upon sudden stopping or starting of the trolley any tendency of the bucket to swing like a pendulum in the plane of the track will be immediately checked and in a very brief interval of time the bucket will be completely motionless relative to the trolley, and may be lowered. Thus the stabilizing device of my invention permits use of a traversing hoist bucket for filling a series of bins, thereby realizing all the advantages of these bins without the disadvantages of damage to the bucket and bins or else the serious loss of time waiting for the bucket to cease oscillation before lowering it. The invention is also useful when filling the bucket from a pit, as a bucket cannot enter a pit when swinging through a considerable arc, but will easily enter a narrow pit if, prior to lowering, it is stabilized by a device embodying the invention.

Obviously the present invention is not restricted to the particular embodiment thereof herein shown and described. Moreover, it is not indispensable that all the features of the invention be used conjointly since they may be employed advantageously in various combinations and sub-combinations.

What I claim is:

1. A traversing hoist comprising, in combination, a trolley movable along a track; a bucket suspended from the trolley by a hoist line; and means for stabilizing the bucket comprising a buffer against which the bail of the bucket strikes when the bucket is raised to its uppermost position; said buffer having resiliently mounted buffer arms of sufficient spread to be engaged by the bail of the bucket although oscillating in a plane transverse to the general plane of the trolley; the free ends of the buffer arms being inclined downwardly so as to guide the bail to a more or less central position relative to the buffer; the parts being so constructed and arranged that pendulum-like oscillation of the bucket is checked by elevating the bucket until the bail strikes the buffer arms.

2. A traversing hoist comprising, in combination, a trolley movable along a track; a pair of sheaves carried by the trolley; a bucket; a bail secured to the bucket; a sheave secured to the bail; a hoist line passing over the trolley sheaves and under the bucket sheave and carrying the bucket; the bucket sheave traveling along the hoist line during traverse of the bucket without varying its position relative to the trolley; means interposed between the bucket and the trolley to take the force of the pendulum-like swings of the bucket caused by sudden starts and stops and quickly to dampen the swings so that the bucket may be lowered without damage; and means to guide the bail of the bucket toward the central part of the swing-dampening means.

3. A traversing hoist comprising, in combination, a trolley movable along a track; a pair of sheaves carried by the trolley; a bucket; a bail secured to the bucket; a sheave secured to the bail; a hoist line passing over the trolley sheaves and under the bucket sheave and carrying the bucket; the bucket sheave traveling along the hoist line during traverse of the bucket without varying its position relative to the trolley; a spring buffer carried by and depending from the trolley and constructed and arranged to check the pendulum-like swings of the bucket caused by sudden starts and stops; and a pair of converging arms to guide the bail of the bucket to a more or less central position relative to the buffer.

4. A traversing hoist comprising, in combination, a trolley movable along a track; a bucket suspended from the trolley by a hoist line; and means for stabilizing the bucket comprising a buffer against which the bail of the bucket strikes when the bucket is raised to its uppermost position; said buffer having resiliently mounted buffer arms of sufficient spread to be engaged by the bail of the bucket although oscillating in a plane transverse to the general plane of the trolley; the parts being so constructed and arranged that pendulum-like oscillation of the bucket is checked by elevating the bucket until the bail strikes the buffer arms.
5. A traversing hoist comprising, in combination, a bucket having a bail; a sheave connected to the upper end of the bail; a hoist line passing around the sheave on the bail; a trolley movable along a track and carrying sheaves over which the hoist line moves during traveling of the trolley; and a buffer interposed between the bail and the trolley and attached to one of said parts, and constructed and arranged so that oscillation of the bucket in a vertical plane is rapidly checked whenever the bucket is elevated so that the bail, buffer and trolley are in contact.
6. A traversing hoist comprising, in combination, a bucket having a bail; a sheave connected to the upper end of the bail; a hoist line passing around the sheave on the bail; a trolley movable along a track and carrying sheaves over which the hoist line moves during traveling of the trolley; the parts being so arranged that the bail normally hangs in the plane of and below the trolley; and a spring buffer secured to the trolley and extending below the same near the ends thereof, and constructed and arranged to be struck by the bail of the bucket, when elevated, to check and stop pendulum-like oscillations of the bucket responsive to sudden changes in velocity of the trolley.
7. A traversing hoist comprising, in combination, a bucket having a bail; a sheave connected to the upper end of the bail; a hoist line passing around the sheave on the bail; a trolley movable along a track and carrying sheaves over which the hoist line moves during traveling of the trolley; the parts being so arranged that the bail normally hangs in the plane of and below the trolley; and means to check and stop pendulum-like oscillations of the bucket comprising a buffer having arms extending below the trolley and substantially at right angles to the general plane of the trolley, and having springs serving to hold said arms normally horizontal and constructed and arranged to be compressed when the bucket bail strikes said arms upon elevation of the bucket.
8. A bucket-stabilizing attachment for bucket-supporting trolleys comprising, in combination, a frame designed to be secured to each end of the trolley and to extend below the trolley, said frames being spaced apart a distance about equal to the length of the trolley; a buffer plate carried by each frame; and coil springs compressed between each frame and each buffer plate and arranged to be further compressed when blows are delivered to the buffer plates.
9. A bucket-stabilizing attachment for bucket-supporting trolleys comprising, in combination, a frame designed to be secured to each end of the trolley and to extend below the trolley, said frames being spaced apart a distance about equal to the length of the trolley; a buffer plate carried by each frame and extending at right angles to and below the trolley; said buffer plates having a sufficient length to insure engagement with a portion of the bucket as the bucket is elevated, and sufficiently spaced below the trolley to prevent any portion of the bucket from striking the trolley; and mechanism carried by each frame for absorbing shocks imparted to the corresponding buffer plate.

WILLIS H. TOWNE.
